(57) **CLAIM**

The ornamental design for a light kit set, as shown and described.

DESCRIPTION

FIG. 1 is a perspective view of a light kit set showing the first and third components in an assembled state, and the second component omitted in order to show aspects of the design not otherwise apparent;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an exploded perspective view thereof;

FIG. 10 is an enlarged view of portion 10 shown in FIG. 1; FIG. 11 is an enlarged view of portion 11 shown in FIG. 2; FIG. 12 is a perspective view of a light kit set showing the second and third components in an assembled state, and the first component omitted in order to show aspects of the design not otherwise apparent;

FIG. 13 is another perspective view thereof;

FIG. 14 is a front elevational view thereof;

FIG. 15 is a rear elevational view thereof;

FIG. 16 is a left side elevational view thereof;

FIG. 17 is a right side elevational view thereof;

FIG. 18 is a top plan view thereof;

FIG. 19 is a bottom plan view thereof;

FIG. 20 is an exploded perspective view thereof;

FIG. 21 is an enlarged view of portion 21 shown in FIG. 12; and,

FIG. 22 is an enlarged view of portion 22 shown in FIG. 13. The dash-dash broken lines in the drawings depict portions of the light kit set that form no part of the claimed design. The dot-dash broken lines represent boundaries of the enlarged portions and form no part of the claimed design. The light kit set is shown with symbolic breaks in its length and the appearance of any portion of the light kit set between the break lines form no part of the claimed design.
